ORIFICE-PROVIDED ELEMENT

Edward S. Cornell, Jr., Larchmont, N. Y., assignor
to American Radiator & Standard Sanitary
Corporation, New York, N. Y., a corporation of
Delaware

Application June 5, 1933, Serial No. 674,326

8 Claims. (Cl. 137—75)

This invention relates to orifice-provided elements.

More particularly, the invention comprises a hollow body provided with end openings and further provided with a lateral opening, a set of orifice-provided elements, the orifices of the respective elements being of different predetermined cross-sectional areas, and retaining means for the selected orifice-provided element whereby upon insertion through the lateral opening and suitable positioning of the same within the hollow body, the orifice of the element effectually controls the flow or rate of flow of fluid through the valve.

Preferably, the orifice-provided element and its retaining means when arranged in position are concealed from tampering, to thus preclude disturbance of the same by unauthorized persons. Advantageously, such purpose is carried out by providing the lateral opening with a closure cap, which may serve also to seal the lateral opening against fluid leakage.

The retaining means, preferably, is provided with effective faces coating with the orifice-provided element, which faces are contoured to engage inner face portions of the hollow body in substantial fluid-sealed relation therewith. The retaining means is advantageously formed to have retaining portions spaced from one another to provide a clearance of predetermined dimension, such clearance serving as a slot, each orifice-provided element having a thickness corresponding to such predetermined dimension to enable the element to be inserted in such slot and effectively held therein, the retaining portions respectively having an outer contour, the faces of which substantially correspond to and engage abutting inner face portions of the hollow body, to preclude or minimize leakage of fluid therat.

In the preferred forms of the invention, each orifice-provided element is further provided with an aperture, which conveniently is a perforation, at a portion thereof accessible within the lateral opening of the valve body, whereby upon removal of the closure cap, the orifice-provided element may be readily withdrawn by insertion of a suitable tool into such aperture and the application of force.

In the most preferred forms of the invention, the retaining member embodies a body portion to which the stated spaced retaining portions are integral or otherwise rigidly secured, the body portion being provided with a slot communicating with the slot of predetermined clearance, each orifice-provided element having an extension ar-

ranged to be inserted through the slot of the body portion, the hollow body being provided at its interior with annular formations, conveniently formed integral with the material of the valve body, the material of the valve body being extended to partially fill the virtual bottom of the lateral opening. Such formations result effectively as or in the nature of a boss; these formations are spaced from one another within the bore of the hollow body and provide a slotted opening accessible through the lateral opening and serves for the reception of the assembled orifice-provided element and its retaining means.

Further features and objects of the invention will be more fully understood from the following detail description and the accompanying drawing, in which

Fig. 1 is a central vertical section of an orifice valve embodying my invention; this view also illustrates the assembly of the orifice valve with piping;

Fig. 2 is a top plan view of Fig. 1, with the closure cap removed;

Fig. 3 is a vertical sectional view, on line 3—3 of Fig. 1;

Fig. 4 is a detail perspective view of a retaining member for retaining an orifice-provided element;

Fig. 5 is a detail perspective view of one "size" of orifice-provided element;

Fig. 6 is a detail perspective view of another "size" of orifice-provided element; and

Fig. 7 is a detail perspective view of an orifice-provided element which is imperforate, that is, of nil "size", serving as a shut off valve.

Referring to the drawing, the body 10 of the valve is of any suitable construction, embodying end openings 11, 12 and a lateral opening 13. Usually, the end openings 11, 12 are in alignment with one another and the lateral opening 13 is normal to the end openings. Tubes or pipes 14, 15 are shown connected to the end openings 11, 12, respectively. Any suitable form of connection may be employed. In the illustrated embodiment such connection is had by a sweated joint, that is to say, the inner faces of the end openings 11, 12 are smooth and dimensioned with respect to the ends of the tubes or pipes 14, 15 to provide for capillary or surface flow of a suitable bonding medium, such as solder, which is usually applied after heating the respective overlapping or telescoped end portions, the solder upon cooling congealing to form a fluid tight joint of sufficient rigidity.

The invention finds wide application in hot

water heating systems and particularly with the use of copper piping. Accordingly, in such use, the material of the body of the orifice valve is copper or copper containing alloy. However, it is understood that the invention is not limited to the use with copper or copper containing piping nor to sweated joint connections.

Suitable orifice-provided means is disposed within the hollow body of the valve through its lateral opening 13 for effectually controlling the flow of fluid through the hollow body. Advantageously, the orifice-provided element is in the form of a plate which is provided with an orifice of any predetermined or desired cross-sectional area. In the commercial practice of the invention, a set of plates is furnished having respectively orifices of different "sizes", for selection of the particular plate having the desired "size" of orifice, to effect the desired regulation of the fluid flow.

To accomplish such and other purposes, I prefer a retaining member 16 comprising essentially the retaining portions 16a, 16a spaced from one another to provide a slot 16b of predetermined clearance, to slidably and frictionally receive and retain the selected orifice-provided plate, having an effective thickness corresponding to the dimension of the predetermined clearance.

A set of orifice-provided plates 17, 18, 19, etc., is illustrated in Figs. 5, 6 and 7. The orifice of the element 17 is indicated at 17a, see Fig. 5, and shown circular in configuration and of a diameter of predetermined "size". The orifice of the element 18 is indicated at 18a, see Fig. 6, which is also shown as circular in configuration. As illustrated, the "size" of the orifice 18a is less than that of the orifice 17a. The element 19 is shown devoid of an orifice, see Fig. 7, in which instance, the fluid flow is nil, that is to say, serving as a shut off valve, applicable under certain circumstances.

The respective spaced retaining portions 16a, 16a, are provided with openings 16e of an effective cross-sectional area greater than the cross-sectional area of the maximum orifice of the set of orifice-provided elements, to afford effective control of the fluid flow by the orifice of the selected orifice-provided element.

For effectiveness of assembly of the selected orifice-provided element and its retaining means 16, and the ready insertion and the ready withdrawal of the assembly through the lateral opening 13, I provide within the longitudinal bore of the hollow body annular formations 20, 20, advantageously integral with the material of the hollow body, such formations including extensions 20a, 20a, see Fig. 2, at the region of intersection of the lateral opening with the longitudinal bore of the hollow body. Such formations result in the provision of the slotted opening 21, see Fig. 2, for the reception of the assembled selected orifice-provided element and its retaining means. By dimensioning and contouring the retaining means 16, in particular its portions 16a, with respect to the slotted opening 21 for making a tight frictional fit therein, the leakage of fluid between the mutually engaging faces is minimized and, if desired, substantially precluded. Nicety of frictional fit in contour and dimension is also made with respect to the mutually engaging faces between the lateral i. e. circular face of the body portion 16c of the retaining means 16 relative to the inner face of the bore of the lateral opening 13, to minimize or preclude possible leakage between the mutually engaging faces is had by the provision of a closure cap 22, which may be provided

with a gasket 23, see Figs. 1 and 3. The gasket 23 is preferably of annular configuration, as appears more fully hereinafter.

By the use of the closure cap 22 it serves also to conceal the orifice-selected element and normally precludes tampering by unauthorized persons. 5

For the ready insertion and withdrawal of the assembly of the selected orifice-provided element and its retaining means 16, each orifice-provided element, say 17, is provided with an upper extension 17b having an aperture or other recess 17c, and combined therewith I provide the body 16c of the retaining means 16 with a centrally located slot 16d through which the extension 17b is passed. Thus, such extension 17b serves as a finger piece for effecting the insertion of the stated combined assembly, and by means of the aperture 17c the combined assembly may be readily grasped and removed by means of a simple tool. 10 20

Such preferred form of the invention further embodies the advantage of affording pressure upon the orifice-provided element by engagement of its upper extension 17b by the closure cap 22 upon tightening of the latter, and coincident with such purpose I provide the lower and lateral arcuate face, see 17d, Fig. 5, of the orifice-provided element 17 in this instance, to have a contour substantially precisely coincidental with the contour of the inner face of the bore of the hollow body 10, as is indicated in Fig. 3. Corresponding parts of the remaining elements of the set of orifice-provided elements are designated by corresponding letter-suffix reference characters, and function in similar manner. 30 35

The closure cap may be applied in any suitable manner, as by mating screw-threading as indicated, or by a friction fit cap, etc.

The element 19, see Fig. 7, conforming in outline to an orifice provided element, such as 17, 18, 40 etc., but not embodying an orifice opening, may be employed for the purpose of complete restriction, that is, to shut-off the flow of the fluid.

My invention is applicable for all suitable systems providing for the flow of fluids of all character, including liquid, gas, and flowable solids and the like; as specific illustrations, I cite hot water heating systems, water piping systems, refrigerating systems, domestic gas and other gas piping systems. 45 50

The advantages of my system are apparent from the herein disclosure. The requirement of individual orifice provided elements in sets respectively having different diameter or other dimensioned orifice openings, effects in practice substantial 55 freedom from tampering by unauthorized persons. The absence of a valve stem or equivalent part accessible exteriorly of the valve body attains the object of concealment, tending toward discouragement of tampering. A lock for the cap operated by key or otherwise may be employed if desired. 60

Whereas I have described my invention by reference to specific forms thereof, it will be understood that many changes and modifications may be made without departing from the spirit of the 65 invention.

I claim:

1. The combination of a hollow body provided with end openings, the hollow body being further provided with a lateral opening, said end openings being constructed to be connected with piping, a member comprising a portion having an opening, said portion being arranged to be inserted into said lateral opening of the hollow body and within the interior of the hollow body, said 70 75 75

- member including an upper portion closely fitting the interior of said lateral opening of said hollow body, said member being provided further with a slot having an opening accessible through the 5 lateral opening of the hollow body when said member is in its inserted position, and an element constructed to be inserted within the slot of said member, said element having a portion provided with a perforation of predetermined cross-sectional area in the portion of said element disposed within said opening-provided portion of said member.
2. The combination of a hollow body provided with end openings, the hollow body being further provided with a hollow lateral body portion provided with an opening of circular interior contour, said end openings being constructed to be connected with piping, a member comprising a portion dimensioned to be received within said 10 hollow lateral body portion and further comprising a thereto transversely extending portion having an opening, said portion being arranged to be inserted into said lateral opening of the hollow body and within the interior of the hollow body, said member including an upper portion of circular contour closely fitting the circular interior of said hollow lateral body portion, said member being provided further with a slot having an opening accessible through the lateral opening 15 of the hollow body when said member is in its inserted position, and an element constructed to be inserted within the slot of said member, said element having a portion provided with a perforation of predetermined cross-sectional area in the portion of said element disposed within said 20 opening-provided portion of said member, said element comprising a portion secured to its stated portion and of reduced dimension to extend through said reduced dimension opening of said 25 slot.
3. The combination of a hollow body provided with end openings, the hollow body being further provided with a lateral opening, said end openings being constructed to be connected with piping, a member comprising a portion having an opening, said portion being arranged to be inserted into said lateral opening of the hollow body and within the interior of the hollow body, said member including an upper portion closely fitting the interior of said lateral openings of said hollow body, said member being provided further with a slot having an opening accessible through the lateral opening of the hollow body when said member is in its inserted position, said opening of said slot 30 having a dimension less than the correspondingly extending dimension of said slot, and an element constructed to be inserted within the slot of said member, said element having a portion provided with a perforation of predetermined cross-sectional area in the portion of said element disposed within said 35 opening-provided portion of said member, said element comprising a portion secured to its stated portion and of reduced dimension to extend through said reduced dimension opening of said slot.
4. The combination of a hollow body provided with end openings of circular contour, the hollow body being further provided with a lateral opening, said end openings being constructed to be connected with piping, a member comprising a portion having an opening, said portion being arranged to be inserted into said lateral opening 40 of the hollow body, and within the interior of the hollow body, said member including an upper portion of circular contour closely fitting the circular contour of said lateral opening, said member being provided further with a slot having an opening accessible through the lateral opening of the hollow body when said member is in its inserted position, said opening of said slot 45 having a dimension less than the correspondingly extending dimension of said slot, an element constructed to be inserted within the slot of said member, said element having a portion provided with a perforation of predetermined cross-sectional area in the portion of said element disposed within said opening-provided portion of said member, said element comprising a portion secured to its stated portion and of reduced dimension to extend through said reduced dimension opening of said slot, and means for locking said element relative to said hollow body.
5. The combination of a hollow body provided with end openings, the hollow body being further provided with a lateral opening of circular contour, said end openings being constructed to be connected with piping, a member comprising a portion having an opening, said portion being arranged to be inserted into said lateral opening of the hollow body and within the interior of the hollow body, said member including an upper portion of circular contour closely fitting the circular contour of said lateral opening, said member being provided further with a slot having an opening accessible through the lateral opening of the hollow body when said member is in its inserted position, said opening of said slot 50 having a dimension less than the correspondingly extending dimension of said slot, an element constructed to be inserted within the slot of said member, said element having a portion provided with a perforation of predetermined cross-sectional area in the portion of said element disposed within said opening-provided portion of said member, said element comprising a portion secured to its stated portion and of reduced dimension to extend through said reduced dimension opening of said slot, and means for locking said element relative to said hollow body.
6. The combination of a hollow body provided with end openings, the hollow body being further provided with a lateral opening of circular contour, said end openings being constructed to be connected with piping, a member comprising a portion having an opening, said portion being arranged to be inserted into said lateral opening of the hollow body and within the interior of the hollow body, said member including an upper portion of circular contour closely fitting the circular contour of said lateral opening, said member being provided further with a slot having an opening accessible through the lateral opening of the hollow body when said member is in its inserted position, said opening of said slot 55 having a dimension less than the correspondingly extending dimension of said slot, an element constructed to be inserted within the slot of said member, said element having a portion provided with a perforation of predetermined cross-sectional area in the portion of said element disposed within said opening-provided portion of said member, said element comprising a portion secured to its stated portion and of reduced dimension to extend through said reduced dimension opening of said slot, and means for locking said element relative to said hollow body.
7. The combination of a hollow body provided with end openings, the hollow body being further provided with a lateral opening, said end openings being constructed to be connected with piping, a member comprising a portion having an opening, said portion being arranged to be inserted into said lateral opening of the hollow body and within the interior of the hollow body, said member including an upper portion of circular contour closely fitting the circular contour of said lateral opening, said member being provided further with a slot having an opening accessible through the lateral opening of the hollow body when said member is in its inserted position, said opening of said slot having a dimension less than the correspondingly extending dimension of said slot, an element constructed to be inserted within the slot of said member, said element having a portion provided with a perforation of predetermined cross-sectional area in the portion of said element disposed 60
- 75

within said opening-provided portion of said member, said element comprising a portion secured to its stated portion and of reduced dimension to extend through said reduced dimension opening of said slot and means for locking said member relative to said hollow body.

8. The combination of a hollow body provided with end openings, the hollow body being further provided with a lateral opening, said end openings being constructed to be connected with piping, a member comprising a portion having an opening, said portion being arranged to be inserted into said lateral opening of the hollow body, and within the interior of the hollow body, said member being provided further with a slot having an opening accessible through the lateral

opening of the hollow body when said member is in its inserted position, said opening of said slot having a dimension less than the correspondingly extending dimension of said slot, an element constructed to be inserted within the slot of said member, said element having a portion provided with a perforation of predetermined cross-sectional area in the portion of said element disposed within said opening provided portion of said member, said element comprising a portion secured to its stated portion and of reduced dimension to extend through said reduced dimension opening of said slot, and means for locking said member relative to said hollow body.
